CENTRIFUGALLY CONTROLLED VARIABLE
RESISTANCE

Ray J. Bright, Los Angeles, Calif.

Application December 20, 1943, Serial No. 515,002

17 Claims. (Cl. 201—48)

This invention relates to a variable resistance, and especially to one that is varied in accordance with speed variations.

In order to practice the invention, a conducting liquid is placed under the influence of centrifugal force; and as the force varies due to a variation in speed, the liquid acts as a movable contact to vary the resistance. Preferably the conducting liquid is mercury, as it has obvious advantages for a centrifugally operated device.

It is one of the objects of this invention to provide a resistance that is continuously variable (as contrasted with one that is varied step-by-step) over a substantial range, by the aid of a conducting liquid contact.

It is another object of this invention to make it possible to adjust or calibrate the resistance in a simple manner; that is, the value of the resistance at any speed may be caused to assume any value between limits.

It is still another object of my invention to provide a device of this character in which the mercury is caused to assume a generally annular form about the axis of rotation, the size of the annulus being a function of the speed. This is accomplished by the provision of a closed chamber for the mercury, at least a portion of the walls of the chamber being yielding, so that, as the centrifugal force increases, the volume of the chamber increases and moves the outer boundary of the annulus further from the axis.

It is accordingly another object of this invention to make it possible to vary the position of the mercury contact in response to speed variations, by the aid of an expanding chamber for the mercury, the volume of which chamber varies with the speed.

It is still another object of this invention to calibrate the resistance by a supplemental variation in the volume of the mercury chamber.

Although mercury is a desirable medium for the conducting liquid, it has a high coefficient of expansion as it is subjected to temperature changes. It is still another object of this invention to compensate for the variation in volume of the mercury, and especially by appropriate increase in the volume of the chamber.

This invention possesses many other advantages, and has other objects which may be made more clearly apparent from a consideration of several embodiments of the invention. For this purpose there are shown a few forms in the drawing accompanying and forming part of the present specification. These forms will now be described in detail, illustrating the general prin-

ciples of the invention; but it is to be understood that this detailed description is not to be taken in a limiting sense, since the scope of the invention is best defined by the appended claims.

5 Referring to the drawing:

Figure 1 is a longitudinal sectional view of an apparatus embodying the invention;

Fig. 2 is a sectional view taken along plane 2—2 of Fig. 1;

10 Fig. 3 is a fragmentary sectional view, similar to Fig. 2, of a modified form of the invention; and Fig. 4 is a view similar to Fig. 3 of a further modified form of the invention.

In the form of the invention illustrated in Figs. 15 1 and 2, use is made of a body of mercury 1, serving as a conducting liquid. The mercury 1 is intended to be placed under the influence of centrifugal force, as by rotation about the axis 2. Under the influence of this centrifugal force, the body of mercury 1 assumes a general annular form, since it is confined to that annular form by the walls of a chamber to be hereinafter described.

20 Upon variation of velocity about the axis 2, the position of the mercury annulus likewise changes.

25 As the velocity decreases, the inner edge 3 of the annulus moves closer to the axis 2. Conversely, upon an increase in velocity, this inner edge 3 moves radially outwardly with respect to the axis.

30 This movement is made use of to control an electric circuit. More particularly, it is used to vary the resistance in the circuit in a continuous manner.

The device is mounted for rotation upon an appropriate shaft 25 by the aid of a metallic sleeve 4. A body 5 formed of a plastic, or other insulation material, is molded over the left hand portion of the outer periphery of sleeve 4. For this purpose, this left hand portion may be roughened so as to provide an adequate frictional grip 40 between the body 5 and the sleeve 4.

The body 5 carries a pair of closely spaced walls 45 6 and 7 extending radially with respect to the axis 2. The passageway 8 between the opposed surfaces of these walls forms a space for the mercury 1. The outer edge of the body 1 is confined by a hollow yielding rubber ring 9. Accordingly, as the liquid pressure increases within the hollow of the ring 9, liquid pressure is exerted by the mercury 1 in all directions against the inner surface of the ring 9, and causes the space defined within the ring to be increased. Inner edge 50 3 of the mercury body 1 moves outwardly as the centrifugal force increases. When there is a decrease of liquid pressure due to a reduction in speed, the yielding ring 9 reduces the space avail-

55

able for the body of mercury 1 and the inner edge 3 moves radially inwardly.

The hollow ring 9 is held in place by the aid of a copper sheath extending around the outer surface of the ring 9 and joined to the walls 6 and 7. The outer edges of the walls 6 and 7 are provided with appropriate seats 13 and 14 engaging the inner edges of the ring 9. The copper sheath is formed in the present instance by the halves 10 and 11. The inner edges of these halves are molded within the walls 6 and 7, and in the straight position illustrated in the lower portion of Fig. 1 by the dot-dash lines. After ring 9 is placed in proper position, the halves 10 and 11 are curved around the outer surface of the ring 9, and are joined by a crimped joint 12 along the outer periphery of the ring 9. Furthermore, in order to strengthen the insulation body 5, a number of ribs or vanes 27 (Fig. 1) may be provided extending from the wall 6.

The body of mercury 1 serves to bridge the space between a pair of conducting members 15 and 16. These conducting members are in the form of flat metallic rings, embedded in the inner sides of walls 6 and 7, and having their opposed surfaces exposed in the chamber 8. The inner edges of these members 15 and 16 are shown as embedded in the hub of body 5. Binding posts for making appropriate connection to the members 15 and 16 may be provided as by the structures 17 and 18 respectively. These binding posts may be formed by screws having their heads molded within body 5 and connected as by conductors 19 and 20 with the conductors 15 and 16 respectively.

The contact established between the metallic members 15 and 16 may be broken upon the exertion of a sufficient centrifugal force; in other words, the device may be used to interrupt or open a circuit upon the occurrence of a definite speed of rotation by the axis 2. However, it is also possible to utilize the variations in position of the inner edge 3 to vary the resistance included in an electric circuit joined to the binding posts 17 and 18.

For this purpose the metallic members 15 and 16 may be formed of resistance material, such as nichrome. They may be provided with a number of projections or teeth, such as indicated at 21 in Fig. 2. These teeth extend for a considerable radial distance. Accordingly, as the inner edge 3 of the mercury varies in its radial position, the circuit connecting the binding posts 17 and 18 includes in parallel, a number of teeth 21, each of variable length. Outward movement to the edge 3 introduces, accordingly, additional resistance in the circuit, because an increased length of the teeth 21 is included in the circuit. Inward movement of the mercury edge 3 reduces the resistance, since the mercury then extends closer to the roots of the teeth 21.

Accordingly, there is a continuous variation in resistance as the speed of rotation varies about the axis 2.

It is possible by an inverted arrangement of teeth to cause the resistance to increase as the speed is reduced. Such an arrangement is diagrammatically illustrated in Fig. 3. In this form the metallic member 22 is shown as having radially inwardly directed teeth 23.

Accordingly, as the inner edge 3 moves outwardly, less and less resistance is included in the circuit. As the edge 3 moves inwardly, the resistance increases.

The number and form of the extensions, such as 21 and 23, may be varied to suit the specific

requirements of the control. In the form shown in Fig. 4, the extensions 24 are curved. The length of each extension 24 is much greater than in the forms shown in Figs. 2 and 3. Accordingly, there is a greater variation of resistance from minimum to maximum, as the inner edge 3 of the mercury body 1 moves outwardly.

It is apparent that the extensions, such as 15, 23, and 24, are all placed in parallel between the binding posts 17 and 18 by the contacting mercury body 1. By proper choice of the number of these extensions, the value of the resistance in the circuit may be determined.

Provisions are made for adjusting the volume of the chamber in which the mercury 1 is located, so as to determine the position of inner edge 3, and thereby to adjust the absolute value of the resistance at any speed. For this purpose, the wall 7 is made flexible. By urging the wall 7 inwardly or toward the left, as viewed in Fig. 1, the width of the space 8 is reduced and the edge 3 of the mercury is accordingly caused to move inwardly. To exert this flexing force, use is made of a flange 25 threaded on the sleeve 4. This flange 25 has a projection 26 provided with a convex surface engaging the wall 7. Operation of the flange 25 on the sleeve 4 serves to determine the pressure exerted against wall 7.

Temperature variations cause corresponding variations in the volume of the mercury 1. This would result in undesired variations in the resistance, in accordance with temperature. By the use of the copper sheath 10-11, these variations in volume of the mercury 1 are caused to be ineffective to vary the resistance. As the temperature increases, the copper sheath 10-11 expands and permits the flexible rubber ring 9 to expand, increasing the volume of the hollow portion of the ring, and thus compensating for the increased volume of mercury. Conversely, a reduction in temperature causes the rubber to contract and to reduce the volume of the ring 9. The inner edge 3 of the mercury body 1 is thus maintained in substantially the same place, independently of temperature variation.

The inventor claims:

1. In a device of the character described, a conducting liquid, rotary means for causing said liquid to be urged away by centrifugal force from the axis of rotation, a conductor having a surface exposed to said liquid, and means forming a yielding boundary for limiting the travel of the liquid from the axis.

2. In a device of the character described, a conducting liquid, and means forming a rotary chamber for the liquid, a resistor in the form of a conductor having one or more extensions exposed to the liquid, said chamber having yielding means defining a boundary for the liquid, for determining the position of the liquid with respect to the axis of rotation of said chamber in accordance with the speed of rotation, said extensions being so arranged that the position of contact between the liquid and the extension is determined by the position of the liquid in the chamber.

3. In a device of the character described, a pair of resistor conductors having opposed surfaces defining a space, a conducting liquid bridging the surfaces, a rotary support for the conductors, to cause the liquid to be urged by centrifugal force outwardly through said space, and a yielding wall at the outer edge of the space.

4. In a device of the character described, a

pair of resistor conductors each having one or more extensions, said extensions having opposed surfaces defining a passage, a conducting liquid bridging the surfaces, a rotary support for the conductors, to cause the liquid to be urged by centrifugal force outwardly through said passage, and a yielding wall at the outer edge of the passage.

5. In a device of the character described, a conducting liquid, means forming a rotary chamber for the liquid, a resistor in the form of a conductor having one or more extensions exposed to the liquid, said chamber having yielding means defining a boundary for the liquid, for determining the position of the liquid with respect to the axis of rotation of said chamber in accordance with the speed of rotation, said extensions being so arranged that the position of contact between the liquid and the extension is determined by the position of the liquid in the chamber, and means for supplementarily varying the volume of the chamber.

6. In a device of the character described, a conducting liquid, rotary means for causing said liquid to be urged away by centrifugal force from the axis of rotation, a conductor having a surface exposed to said liquid, means forming a yielding boundary for limiting the travel of the liquid from the axis, and means acting on said yielding boundary, in response to temperature variations, for compensating for variations in the volume of the liquid in accordance with the temperature.

7. In a device of the character described, a conducting liquid, means forming a rotary chamber for the liquid, a resistor in the form of a conductor having one or more extensions exposed to the liquid, said chamber having a yielding means defining a boundary for the liquid, for determining the position of the liquid with respect to the axis of rotation of said chamber in accordance with the speed of rotation, said extensions being so arranged that the position of contact between the liquid and the extension is determined by the position of the liquid in the chamber, and means acting on said yielding means, in response to temperature variations, for enlarging the space for the liquid in accordance with the temperature.

8. In a device of the character described, means forming a rotary chamber, said means including a flexible wall, a solid electrical conductor in the chamber, a liquid electrical conductor in the chamber for co-operating with said solid conductor, means for altering the position of the liquid with respect to the solid conductor, in accordance with the speed of rotation of the chamber, and adjustable means for flexing said wall for altering the volume of the chamber and thereby supplementarily altering the position of the liquid.

9. In a device of the character described, means forming a rotary chamber having opposed walls forming a radially extending passageway, resistor conductors supported on the walls, a liquid electrical conductor in the passageway for connecting said conductors, one of said walls being flexible, and means for flexing said flexible wall for altering the volume of the chamber.

10. In a device of the character described, means forming a rotary chamber having opposed walls forming a radially extending passageway, resistor conductors supported on the walls, and a liquid electrical conductor in the passageway for connecting said conductors, said chamber including an annular recess in communication with said passageway, and formed of an elastic

member, capable of expanding in response to fluid pressure exerted within the recess by said liquid.

11. In a device of the character described, means forming a rotary chamber having opposed walls forming a radially extending passageway, resistor conductors supported on the walls, a liquid conductor in the passageway, said chamber including an annular recess in communication with said passageway, and formed of an elastic member, capable of expanding in response to fluid pressure exerted within the recess by said liquid, and a metallic sheath for said elastic member and having a coefficient of expansion such as to enlarge the recess as the temperature increases, to provide compensation for expansion of the liquid.

12. In a device of the character described, a metallic sleeve, a body mounted on the sleeve and formed of insulation material and having radially extending walls defining a space, one of said walls being flexible, conductors carried by the walls and having surfaces exposed in said space, a liquid electrical conductor in the space for connecting said conductors, and an adjusting member threaded on the sleeve and adapted to flex the flexible wall to vary the volume of the space.

13. In a device of the character described, a metallic sleeve, a body mounted on the sleeve and formed of insulation material and having radially extending walls defining a space, one of said walls being flexible, resistor conductors carried by the walls and having surfaces exposed in said space, said surfaces having extensions, a liquid conductor adapted to form an annular conducting bridge when the sleeve is rotated, the liquid bridge being capable of intersecting said extensions at variable speeds of the sleeve, and means mounted on the sleeve for flexing said flexible wall to adjust the volume of said chamber.

14. In a device of the character described, a metallic sleeve, a body mounted on the sleeve and formed of insulation material and having radially extending walls defining a space, one of said walls being flexible, resistor conductors carried by the walls and having surfaces exposed in said space, said surfaces having extensions, a liquid conductor adapted to form an annular conducting bridge when the sleeve is rotated, elastic means defining an annular recess at the outer edge of said space, said liquid bridge thereby intersecting the extensions under the influence of varying speeds of rotation of the sleeve, and for a range of speed variations.

15. In a device of the character described, a pair of rotatable, radially extending, axially spaced conductors, one of said conductors being a resistor, the resistance of which is a function of the distance of a connection to the resistor, from the axis of rotation, and a conducting liquid resiliently confined between said conductors, and adapted to form a surface movable radially outwardly therebetween in response to rotation of said conductors, to connect the conductors at a distance from the axis varying with the speed of rotation, whereby said resistance varies in accordance with said speed.

16. In a device of the character described, a pair of rotatable, radially extending, axially spaced conductors, one of said conductors being a resistor, the resistance of which is a function of the distance of a connection to the resistor, from the axis of rotation, a conducting liquid resiliently confined between said conductors, and

adapted to form a surface movable radially outwardly therebetween in response to rotation of said conductors, to connect the conductors at a distance from the axis varying with the speed of rotation, whereby said resistance varies in accordance with said speed; and means for adjusting the space between the conductors to vary the resistance independently of the speed.

17. In a device of the character described, a pair of rotatable, radially extending, axially spaced conductors, one of said conductors being a resistor, the resistance of which is a function

5 of the distance of a connection to the resistor, from the axis of rotation, means including a resilient member encircling said conductors forming a closed space between said conductors, and a conducting liquid in said space adapted to form a surface movable radially outwardly therebetween in response to rotation of said conductors, to connect the conductors at a distance from the axis varying with the speed of rotation, whereby said resistance varies in accordance with said speed.
